F. OBERST

TONE ARM

Filed June 6, 1919

Inventor

UNITED STATES PATENT OFFICE.

FRANK OBERST, OF GLENDALE, NEW YORK, ASSIGNOR TO SONORA PHONOGRAPH CORPORATION, A CORPORATION OF NEW YORK.

TONE ARM.

Application filed June 6, 1919. Serial No. 302,105.

To all whom it may concern:

Be it known that I, FRANK OBERST, a subject of the Kingdom of Rumania, and residing at Glendale, in the borough of 5 Queens, county of Queens, and State of New York, have invented certain new and useful Improvements in Tone Arms, of which the following is a specification.

My invention relates to tone-arms for 10 talking machines, and has for its objects to provide means for facilitating the removal and renewing of the stylus.

A further object is the production of a 15 tone-arm having relatively movable members, and wherein rattling will be prevented and eliminated, and in which the various elements which go to make up the tone-arm will be rigidly secured together and easily and readily assembled and disassembled, 20 and accidental displacement avoided.

A further object of the invention is to 25 produce a device of the character described, which is simple in construction, neat and attractive in appearance, thoroughly reliable and efficient in its purpose, positive in operation, and inexpensive and economical to manufacture.

With these and other objects in view to 30 be more fully set forth hereinafter, the invention consists in the novel construction, combination of elements and arrangement of parts which will be exemplified in the construction hereinafter described in the specification and illustrated in the accompanying drawings, considered together or 35 separately.

The invention will be first described in 40 connection with the accompanying drawings illustrating my invention, wherein similar reference characters are used to designate corresponding parts throughout the several views, and then more specifically defined and indicated in the appended claim.

In the drawings:

Fig. 1 is a side elevation, partly in section, 45 of a tone-arm embodying my invention;

Fig. 1^a is a detailed sectional view of the clamping means indicated in Fig. 1;

Fig. 2 is a section on the line 2—2 of 50 Fig. 1;

Fig. 3 is a detail sectional view of a modification, the section being indicated by the line 3—3 on Fig. 4; and

Fig. 4 is a section on the line 4—4 of 55 Fig. 3.

In the embodiment of the invention illustrated, 1 designates the main portion of a tubular tone-arm, which is mounted to swing horizontally only on the motor board 2 of a talking machine cabinet. The free 60 end of this main portion of the tone-arm 1 is provided with cylindrical barrel 3, the axis of which is at right angles to that of the horizontal portion of the tone-arm, and in communication therewith. The barrel 65 3 is closed at one end by means of an integral head 4, and at the opposite end is open and internally screw threaded and closed by means of an externally screw threaded cap 5 which is threaded into the 70 end of the barrel and provided with a milled edge flange 6 flush with and of the same diameter as the outside of the barrel. One side of the barrel is cut away as at 7, to form a slot which extends approximately 75 half way around the barrel. The end of the tone-arm 1 to which the barrel is attached, is reduced in diameter.

Within the barrel is a cylindrical plug or 80 swivel 9 having a bore 10, therethrough. The diameter of the bore is equal to that of the diameter of the reduced end of the tone-arm 1. Between the end of the swivel 9 and the cap 5 is disposed a washer 11 of felt or similar porous material which is preferably 85 saturated with oil or a similar lubricant.

Carried within the bore 10 of the swivel 9 is a tubular member 12 which forms an extension of the tone-arm.

The member 12 has a close fit in the bore, 90 and a screw or pin 13 is passed through one end of the swivel and into the member 12, whereby the swivel and member are firmly secured together. The free end of the member 12 carries a reproducer 14 provided with 95 a stylus for engagement with a record disc 15 carried on a turn-table 16.

On the inside of that end of the member 12 which lies within the swivel is secured 100 a spring 17 provided with a rounded pin 18. The pin projects through a perforation 19 in the member 12 and a notch in the edge of the plug or swivel and projects into the slot 7 of the barrel. The pin 18 is adapted 105 to engage a perforation 20 in the barrel 3 to lock the extension member 12 in the elevated position shown in dotted lines in Fig. 1.

In assembling the parts as above described 110 the plug or swivel 9 is first fitted or slid into

the open end of the barrel 3, and then the inner end of the extension 12 with its attached spring and pin inserted through the slot in the barrel 3 and into the bore 10 of 5 the plug or swivel 9, the pin 18 serving to limit the inward movement of the extension and to position the extension in the plug or swivel, and the screw 13 is then put in place through the open end of the barrel 10 to secure the extension 12 in place. The washer 11 is then placed in the barrel adjacent to the plug or swivel and the cap 5 secured to place against the washer to hold the parts in engagement to prevent 15 rattling, and it will be observed that the cap may be tightened up to take up looseness in the joint which may be caused by use.

In the modification shown in Figs. 3 and 4, one extremity of the swivel is reduced in diameter as at 21, to form an annular chamber 22 in the barrel. Secured to the reduced portion 21, and lying within the chamber 22 is a spring 23 carrying a pin 24 adapted to engage a perforation 25 in the barrel when the member 12 is elevated or in the position shown in Fig. 4 and in dotted lines in Fig. 1. The perforation 25 is preferably in the underside 20 of the barrel, as shown in Figs. 3 and 4, and is therefore invisible or concealed from sight.

Carried on the tone-arm 1, in proximity to the vertical axis thereof is an arm 26 adapted to extend under the turn-table and engage and operate a trip for an automatic stop (not shown) for arresting the rotation of the motor and stopping the turn-table. The arm is carried on a stem 27 which is provided with a cylindrical socket 40 at its upper end. The socket has a split side 29 and a screw 20 passes through a perforation 31 to clamp the socket to a pin 32 carried by the tone-arm. The lower end of the pin is provided with a peripheral groove 33 with which the screw engages to permit removal of the socket and at the same time permit rotation of the socket 45 relatively to the pin.

It will be understood that the construction of tone-arm herein with the swivel extension, and wherein the main portion of the tone-arm is swiveled to the motor board or cabinet to have a horizontally swinging movement only, is particularly 50 adaptable to those talking machines provided with an automatic stop or braking mechanism wherein the tripping mechanism for the stop or brake is located beneath the turn-table, and it is necessary to provide 55 an arm for operating said trip carried by the tone-arm extending under the turn-table, thus making it undesirable to attach 60

such operating arm to a tone-arm which is swiveled to the motor board to have both a horizontal movement and a vertical adjustment, as such operating arm would prevent the lifting or vertical adjustment of the tone-arm in removing the stylus from the record and for other purposes.

In accordance with the provisions of the patent statute, I have described the principle of my invention together with the apparatus which I now consider to represent the best embodiment thereof, but I desire it is understood that my invention is not confined to the particular form of apparatus herein shown and described, and, therefore, I claim broadly the right to employ all equivalent instrumentalities coming within the scope of the appended claim, and by means of which objects of my invention are attained, and the new results accomplished, as herein set forth, as it is obvious that the particular embodiment herein shown and described is only illustrative of my invention and that other means can be employed to attain these objects and accomplish these results without departing from the spirit of my invention.

Having now described my invention, what I claim and desire to secure by Letters Patent is:

A tone-arm for talking machines, comprising a horizontally swinging main portion provided at its outer end with a barrel having an integral head closing one end thereof and open and interiorly screw-threaded at its other end, said barrel having a circumferential slot, a swivel head having a radial bore and adapted to be fitted endwise in the barrel through the open end thereof, an extension for said tone-arm adapted to be inserted through the slot in said barrel and detachably fixed in the bore of said swivel head, an absorbent lubricant containing washer fitted in the open end of said barrel and engaging the end of said swivel head, and a plug cap for the open end of said barrel having a reduced externally screwthreaded portion adapted to engage the interiorly screwthreaded end of the barrel to hold the washer and swivel head in place and provided with a milled edge flange adapted to engage the edge of the barrel and substantially of the same diameter and flush with the outer circumference of the barrel.

This specification signed and witnessed this 23rd day of May, 1919.

FRANK OBERST.
